UNITED STATES PATENT OFFICE.

JOHN T. HORTON, OF NEW YORK, N. Y.

FALL-ROPE CARRIER.

1,120,145.

Specification of Letters Patent.

Patented Dec. 8, 1914.

Application filed April 21, 1913. Serial No. 762,561.

To all whom it may concern:

Be it known that I, JOHN T. HORTON, a citizen of the United States, and a resident of New York, borough of Brooklyn, in the county of Kings and State of New York, have invented certain new and useful Improvements in Fall-Rope Carriers, of which the following is a specification.

This invention relates to fall rope carriers for cableways.

The object of my improvements is to provide positive means for causing said carrier to traverse the supporting cable and at a predetermined ratio of speed relatively to the speed of the driving line.

Another object of my improvements is to provide means for readily changing any given ratio of speed to some other ratio.

Other objects of my improvements will appear in the specification and be particularly pointed out in the claims.

With these objects in view the preferred form of my improvements is illustrated in the accompanying drawings wherein—

Figure 1 is a side elevation of my fall rope carrier and Fig. 2 is a sectional elevation on line 2, 2 of Fig. 1.

Before describing the invention in detail I desire to have it understood that the invention is not limited to the particular construction and arrangement of parts which I have illustrated and shall herein-after describe, and that various changes may be made in the mechanism without departing from the spirit or scope of the invention, and that the phraseology which I employ is for the purpose of description and not of limitation.

My improvements are herein illustrated as applied to that type of fall rope carrier set forth in Letters Patent of the United States Number 1003261, granted September 12, 1911, on the joint invention of myself and Edward H. Deline. It will be obvious however to those skilled in the art that my present improvements are equally applicable to a wide variety of types of fall rope carriers and are not restricted to the particular type illustrated.

In the figures of the drawing 3 is the usual supporting cable, 4 is the driving or traction line, 4^a the return run thereof and 5 is the hoisting or fall rope. Two supporting cable traverse wheels 7, 8 are rotatably mounted on fixed axes supported between horizontal side frames 9, 10. For stability

said side frames may be secured to end blocks as 6. Depending side arms 11, 12 are fixed at their upper ends midway the length of side frames 9, 10 respectively and have rotatably mounted therebetween the usual wheels 13, 14 for supporting the return run 4^a of driving line 4 and fall rope 5 respectively. Preferably mounted coaxially with cable traverse wheels 7, 8 are driving wheels 15, 16 respectively. These driving wheels may be of some convenient diameter and are free to rotate independently of their respective coaxial traverse wheels. Gripper wheels 19, 20 are provided for engagement with the underside of cable 3 and are rotatably actuated from traverse wheels 7, 8 respectively by means to be hereinafter described. These gripper wheels are also urged upwardly to grip cable 3 between them and traverse wheels 7, 8 respectively. Said gripper wheels 19, 20 are rotatably mounted in the free ends of arms 21, 22 respectively. Said arms are pivotally mounted at their upper ends in convenient positions in side frames 9, 10 on pivots 23, 24, said pivots preferably being concentric with wheels 7, 8 all respectively. Said arms 21, 22 are preferably double arms as 21, 21^a on each side of wheel 19.

To cause wheels 19, 20 to grip the underside of cable 3 I provide tension wheel 26 for engagement with the upper side of driving line 4. Said tension wheel is rotatably mounted at 31 in the upper ends respectively of links 27, 28, the lower ends of said links being pivotally attached to arms 21, 22, preferably at 29, 30, coaxially with gripper wheels 19, 20 respectively. Thus the upward urge of line 4 under tension wheel 26 will cause that wheel, through links as 27, to pull upwardly gripper wheels as 19 to engagement with the under side of cable 3.

As my improved device, in that embodiment thereof chosen for illustration, is symmetrical relatively to a vertical plane through the axes of wheels 13, 14 Fig. 1, a further description of those parts on one side of that plane will suffice for both.

For causing gripping wheel 19 to rotate and thus advance the carrier along cable 3 and I provide driving wheel 15 with gear 17 fixed thereto and concentric therewith and I provide driving wheel 15 with gear 18 similarly fixed thereto, said gears being in mesh. Wheel 19 is fixed to shaft 29 by pin 25 and gear 17 is removably fixed to

that shaft by key 32. Wheel 15 is fixed to sleeve 33 by pin 34 and gear 18 is removably fixed to that sleeve by key 35. Said gears 17, 18 may therefore be readily removed from their respective positions and interchanged or gears of other sizes substituted, thereby varying at will the ratio of rotation of wheels 15 and 19. Wheel 15 is preferably of larger diameter than wheel 19 so that the traction of driving line 4 may be depended upon to rotate that wheel against the resistance of the train including gears 18, 17 and wheel 19 and cause said wheel 19 to rotate against cable 3 and drive the fall rope carrier along that cable. To provide added efficiency for such drive, I, in some cases, provide wheel 19 with gear 36 fixed thereto for driving gear 37 of wheel 7. Said wheels are illustrated as of equal diameter and said gears will therefore be of equal diameter as shown.

I claim:

1. A fall rope carrier including in combination two supporting cable traverse wheels for engaging the upper side of the supporting cable, a driving wheel for engaging the under side of the driving line, a gripping wheel for engaging the under side of the supporting cable, a tension wheel for engaging the upper side of the driving line, means for driving said gripping wheel from said driving wheel, and means for driving one of said traverse wheels from said gripping wheel.
2. A fall rope carrier including in combination two supporting cable traverse wheels rotatably mounted in fixed relation to each other for engaging the upper side of the supporting cable, a driving wheel mounted coaxially with one of said traverse wheels but rotatable independently thereof for engaging the under side of the driving line, a gripping wheel for engaging the under side of the supporting cable, means for driving said gripping wheel from said driving wheel, a swinging arm, one end of which is mounted in fixed relation relatively

to one of said traverse wheels and in the other end of which is mounted said gripping wheel, a tension wheel for engaging the upper side of the driving line and mounted for movement toward and away from said driving line and means connecting said tension and gripping wheels for causing said gripping wheel to engage the supporting cable.

3. A fall rope carrier including in combination two supporting cable traverse wheels for engaging the upper side of the supporting cable, a driving wheel for engaging the under side of the driving line, a gripping wheel for engaging the under side of the supporting cable, a tension wheel for engaging the upper side of the driving line, geared connections between said driving wheel and said gripping wheel, and geared connections between one of said traverse wheels and said gripping wheel.

4. A fall rope carrier including in combination two supporting cable traverse wheels rotatably mounted in fixed relation to each other for engaging the upper side of the supporting cable, a driving wheel mounted coaxially with one of said traverse wheels but rotatable independently thereof, for engaging the under side of the driving line, a gripping wheel for engaging the under side of the supporting cable, a tension wheel for engaging the upper side of the driving line and mounted for movement toward and away from said driving line, geared connections between said driving wheel and said gripping wheel, and geared connections between one of said traverse wheels and said gripping wheel.

Signed at New York, in the county of New York and State of New York, this 17th day of April, 1913, before two subscribing witnesses.

JOHN T. HORTON.
